Patented Oct. 17, 1922.

FIG. 1

FIG. 2

FIG. 3

INVENTOR
William H. Hutchins
by his attorney
Farnum T. Dorsey

UNITED STATES PATENT OFFICE.

WILLIAM H. HUTCHINS, OF ROCHESTER, NEW YORK, ASSIGNOR TO NORTH EAST ELECTRIC COMPANY, OF ROCHESTER, NEW YORK, A CORPORATION OF NEW YORK.

IGNITION TIMER.

Application filed February 26, 1920. Serial No. 361,528.

To all whom it may concern:

Be it known that I, WILLIAM H. HUTCHINS, a citizen of the United States, residing at Rochester, in the county of Monroe 5 and State of New York, have invented certain new and useful Improvements in Ignition Timers; and I do hereby declare the following to be a full, clear, and exact description of the invention, such as will enable others skilled in the art to which it 10 pertains to make and use the same.

This invention relates to the timing devices in electric ignition-apparatus for engines. In such apparatus it is common to 15 employ a circuit-controller having a cam, or other rotary member, which is driven by connection with the mechanism of the engine, and which cooperates with other members mounted in a normally stationary 20 position within a head or casing. The timing of the ignition may be manually adjusted, in such an arrangement, by a partial rotation of the casing or head about the axis of rotation of the cam or rotary-member. 25 The circuit-controller, and it is customary to provide stops of some sort for limiting such partial rotation so as to prevent the time of ignition from either being too far advanced or too far retarded.

30 The object of the present invention is to provide an ignition-timer, of the type in question, with simple and effective means for limiting the rotative adjustment as aforesaid, such means being preferably so 35 formed that they may be readily adjusted to various positions according to the particular location and manner in which the ignition-timer is to be applied and used.

To the foregoing end it is proposed to 40 interpose, between the adjustable head and the support upon which it is mounted, a stop-member, preferably of annular form, and to connect the stop-member with the head and with the support, respectively, by 45 means of cooperating recesses and abutments so arranged as to permit the necessary limited amount of relative rotation between the members of the timer. In the most complete embodiment of the invention the 50 stop-member and one or another of the members with which it cooperates is provided with a series of such abutments of recesses adapted for alternative engagement with the corresponding parts, and the 55 stop-member is conveniently mounted and

secured in place by being arranged to surround the stem of the timer-head and rest upon the bearing-member or support in which this stem turns.

In the accompanying drawings Fig. 1 is 60 a side-elevation of an ignition-timer embodying the present invention, the stop-member and the supporting-member being shown partly in section. Fig. 2 is a partial side-elevation of the same parts, looking 65 from left to right in Fig. 1. Fig. 3 is a perspective view of the stop-member alone, on a slightly larger scale than the other figures.

The invention is illustrated as employed 70 in connection with an ignition-timer having the usual head 5 within which the circuit controller is located. This head is mounted upon a stem 6 which forms the bearing for the shaft 7 by which the circuit-controller is actuated. This shaft is driven through gears 8, connected in any ordinary or suitable manner with the mechanism of the engine with which the timer is used.

The gears are inclosed in a housing 9, which is provided with an upwardly projecting sleeve 10. This sleeve constitutes the support or bearing for the head 5 and the stem 6, the latter being arranged to turn 80 freely in the sleeve and being held therein by means of a screw 11 which engages an annular groove in the stem. The head 5 is provided with an arm 12 by which it may be turned to vary the time of ignition, and this arm is provided with a depending lug 13 adapted to cooperate with stops to limit the adjusting movement of the casing.

The parts so far described are or may be of ordinary form, and the present invention resides particularly in the form and arrangement of a stop-member which is interposed between and connected with the head and the support. This stop-member is shown as formed of sheet-metal and comprises a 95 flat annular portion or ring 14, provided at its outer edge with a lateral projection on which are two upstanding stop-lugs 15. The ring 14 is arranged to surround the stem 6 and rest upon the upper end of the 100 sleeve 10, and it is prevented from rotating upon the sleeve by means of a dowel-pin 16, which is fixed in the sleeve and engages one or another of a series of recesses 105 or perforations 17 in the ring. The stop- 110

2
lugs 15 lie on each side of the stop-lug 13, so as to limit the movement of the latter and thus determine the range of rotative adjustment of the head. The dowel-pin 16 5 may be engaged with any one of the 8 holes 17 alternatively, so that there are eight possible positions of the stop-ring. In each of these positions the range of adjustment of the timer-head is the same, but the lever 12 10 will project in a different direction with respect to the stationary parts of the apparatus. The mechanism may thus be adapted for use upon either the right or the left-hand side of an engine, and in connection 15 with various arrangements and constructions of the means employed for connecting the lever 12 with the manually operable means by which the time of ignition is controlled.

20 The invention is not limited to the embodiment thereof hereinbefore described and illustrated in the accompanying drawings, but it may be embodied in various other forms within the terms of the following 25 claims.

The invention claimed is:

1. In an ignition-timer, the combination, with two relatively rotatable members comprising a circuit-controller and a support 30 therefor, of means, for limiting the relative rotation of said parts, comprising a ring provided with a series of recesses; an abutment on one of said parts adapted to engage said recesses alternatively; and abutments, on the ring and the second of said parts, cooperating to limit relative rotation of the ring and said second part.
2. In an ignition-timer, the combination, with two relatively rotatable members comprising a circuit-controller and a support 35 therefor, of a stop for limiting the relative rotation of said members, said stop being normally fixed but being adjustable to different angular positions about the axis of rotation of said members.
3. In an ignition-timer, the combination, with two relatively rotatable members comprising a circuit-controller and a support 40 therefor, of means, for limiting the relative rotation of said parts, comprising an annu-

lar stop plate provided with recesses; and abutments, on said members, engaging said recesses and adapted to permit limited relative rotation of one of said members and said annular stop plate.

4. In an ignition-timer, the combination of three members comprising a circuit-controller, a support therefor, and a stop-member; the circuit-controller being rotatable on the support; the stop-member and each of the other said members being provided with stop-points in the form of cooperating recesses and abutments whereby relative rotation of the stop-member and each of the other members is limited; and said stop-points on one of said members being duplicated and arranged in a series alternatively operable to adjust the position of the range of rotative movement of the circuit-controller.

5. In an ignition-timer, the combination of a support provided with a bearing; a circuit-controller provided with a stem supported and rotatable in said bearing; a stop-member in the form of a ring surrounding said stem; cooperating means on the stop-member and the support for limiting rotative movement of the stop-member, relatively to the support, about the axis of said stem; and cooperative means, on the stop-member and the circuit-controller, for limiting relative rotation of the circuit-controller and the stop-member.

6. In an ignition-timer, the combination of a support provided with a vertical bearing; a circuit-controller provided with a depending stem rotatable in said bearing; a stop-member comprising a ring, loosely surrounding said stem and resting on the support, and two lugs projecting from the ring, the ring being provided with a circular series of perforations; a pin projecting from the support and engageable with said perforations alternatively; and a projection, on the circuit-controller, movable between the lugs on the stop-member whereby the rotation of the circuit-controller relatively to the support is limited.

WILLIAM H. HUTCHINS.
